UNITED STATES PATENT OFFICE.

WILLIAM B. HAYDEN, OF COLUMBUS, OHIO.

BUCKLE.

SPECIFICATION forming part of Letters Patent No. 236,809, dated January 18, 1881.

Application filed May 7, 1880. (Model.)

To all whom it may concern:

Be it known that I, WILLIAM B. HAYDEN, of Columbus, in the county of Franklin and State of Ohio, have invented a new and useful Improvement in Harness-Buckles, of which the following is a specification.

My invention relates to that class of harness-buckles in which a beak or hook is provided by connecting the buckle with a ring or eye of a snap-hook, and in which the strap is passed through loops and secured upon a stud that is formed upon the frame or body of the buckle.

The object of my invention is to relieve the strap from an excess of strain at the point where it is secured upon the stud, since in buckles of this class, as heretofore made, an undue strain at such point has occasioned the frequent tearing of the strap; and a further object of my invention is to keep the strap down upon the stud by carrying a portion of the strap itself over the stud, so as to bear thereon and confine the free end of the strap thereon.

To such end my improvement consists, essentially, in elevating the bar upon which the stud is formed between two loops in a buckle, hereinafter to be described, so that after the end of the strap has been passed under the loops and then carried around the beak or hook, and thence back to the stud upon which it is secured, that portion of the strap which lies between the two loops will bear upon the top of the stud, as hereinafter more fully described.

In the drawings, Figure 1 is a perspective view of a harness-buckle embodying my invention. Fig. 2 is a perspective view of the buckle connected with a snap-hook, the strap being shown applied to the buckle, but not drawn tight. Fig. 3 is a central longitudinal section with the strap drawn tight in the buckle.

The harness-buckle herein illustrated consists of a skeleton-frame, in which A A are the side bars, connected at their rear ends by a flat bar or loop, B. These side bars terminate at their forward ends in a plate, C, in which is formed a rectangular recess, D, that gives lightness to such portion. The forward end of this plate is reduced in width, so as to form a tongue, that is bent upward and then back to constitute the hook or beak E of the buckle.

The metal of the side bars is raised, as at the points f f, and such raised portions connected by a middle bar or loop, F, which lies at a point between the rear loop, B, and the beak or hook. Between this middle loop, F, and the rear loop, B, the side bars are connected by a cross-bar, G, which is slightly curved in cross-section. On this cross-bar is formed the stud H, upon which the end of the strap H' is to be secured. Those portions of the side bars which are between the rear and the middle loops of this buckle are not made straight, but are curved upward, as at I, so as to elevate, to a certain extent, between said loops, the bar upon which the stud is formed, and hence so raise the stud that its top end is about in the same plane as the top side of the rear loop, B. The advantage of thus elevating said cross-bar and stud will be seen by referring to Fig. 3, in which the strap is shown applied to the buckle.

The manner of applying the strap is as follows: Its end is first passed under the two loops and over the stud, then carried around the beak, upon which a ring or snap-hook has been previously caught, and then passed back under the buckle to the cross-bar having the stud, at which point the said strap end is slightly raised through the skeleton-frame and caught upon the stud. If, now, the strap be drawn tight, it will lie in the position shown in said last-mentioned figure.

It will be observed that while the end of the strap is caught upon and held by the stud a portion of the rear part of the strap rests upon the top of the stud, and that such portion of the strap as is located between the two loops lies in the line of an arc of a circle. This not only prevents the end of the strap from accidental disconnection from the stud, but also relieves the strap from a greater portion of the strain at its point of connection with the stud, and hence obviates the tearing of the strap.

It will also be seen that the strain upon the strap is distributed from its point of connection with the stud around the buckle, so that under any circumstances it will be impossible to tear the strap from the stud to which it is fastened.

It will also be noticed that by forming the recess in the plate near and under the beak or

hook, as herein shown, the necessity of employing a core in casting such portion of the buckle is avoided.

What I claim is—

5 The herein-described buckle, composed of two side bars connected by a rear end and a middle loop, and terminating at their forward ends in a recessed plate, bent at its reduced end into a hook or beak, and the elevated 10 cross-bar connecting raised portions of the side bars at points between the two loops, and provided with a stud upon which the end of

the strap is secured, said cross-bar and stud being elevated, so that after the strap has been 15 passed under the loops and around the beak and secured upon said stud the straps lying between the loops will bear upon the stud and confine the free end of the strap thereon, substantially as described.

WILLIAM B. HAYDEN.
